UNITED STATES PATENT OFFICE.

JOHNSON HUGHES, OF PHILADELPHIA, PENNSYLVANIA.

ROLLING-MILL MANIPULATOR.

1,183,980.

Specification of Letters Patent. Patented May 23, 1916.

Application filed July 10, 1913. Serial No. 778,295.

To all whom it may concern:

Be it known that I, JOHNSON HUGHES, a citizen of the United States, residing at Philadelphia, in the county of Philadelphia and State of Pennsylvania, have invented certain new and useful Improvements in Rolling-Mill Manipulators, of which the following is a specification.

My invention relates to an apparatus especially adapted to manipulate, *i. e.* to move, turn and straighten the hot ingots, billets or slabs before they enter into certain passes of the reducing rolls of a blooming or rolling mill, and to shift them from one pass to another of the rolls.

In designing my improved manipulator and which now is in practical use, I have succeeded in overcoming the general difficulties and have provided an apparatus which is prompt in action, capable of turning a long or short ingot located at any point on the roller bed within reach of the manipulator, and by which ingots, billets or slabs may be turned which are not entirely straight; that is, such metal which has become bent or curved during the rolling operations. The apparatus further is capable of straightening the billet or slab before entering another pass of the rolls, and its actions in performing these duties are prompt and decisive and yet flexible, *i. e.*, the operating parts do not come into contact with the metal being rolled with a hard blow, but engage the same gradually, thereby saving repair expense, loss of time in mill due to such repairs, etc.

My improved manipulator consists principally of a tilting cheek plate movable from one side of a roller bed to the other, a vertically disposed cheek plate adapted to move from the other side of the roller bed toward and beyond the center of the roller bed, and of mechanism and apparatus for moving the said cheek plates for the purposes above stated. All of the mechanism and apparatus are located above the roll pit so that easy access is had to every part thereof if repairs become necessary.

My invention will be more readily understood by references to the accompanying drawings, wherein,

Figures 1 and 2, placed side by side, illustrate in plan a roller feed table or conveyor equipped with my novel manipulating device; Fig. 3 is a transverse vertical sec-

tion on the line 3—3 of Fig. 1; Fig. 4 is an end elevation of the construction shown in Fig. 2, and Fig. 5 is a side elevation of the construction shown in Fig. 1. Fig. 6 is a detail sectional elevation on the line VI—VI 60 of Fig. 3. Fig. 7 is a detail sectional elevation on the line VII—VII of Fig. 4.

Referring now to the drawings for a further description of my invention, it will be seen that I provide a roller bed immediately in front of rolls 10. The roller bed consists of rolls 11, supporting the ingot, billet, slab or other piece of hot metal and adapted to move the same toward or away from the reducing rolls 10. These rolls contain a number of passes, and the object of the manipulator is to turn and shift the metal from one pass to another, as may be required in the process of reducing the cross section of an ingot to form the bloom, billet, slab or other section into which the metal is rolled. For this purpose a tilting cheek plate 12 is arranged on one side of the roller bed and a vertical cheek plate 13 on the other side of the bed. The construction and operation of the tilting cheek plate 12 is the most important as it principally serves to turn the billet and its construction will now be described. The lower edge of the cheek plate extends below the top of the rollers 11, and is provided with a fulcrum 14, hinging the lower edge to brackets secured to a bed plate 16. Below each bracket 15, and supported on the roller bed foundation, are V-shaped guide rails 17, and grooved wheels 90 fitting these rails are journaled in the said brackets 15, which carry the bed plate 16, in its movement laterally across the roller bed. On the drawings the cheek plate 12 is shown in full lines in an inclined position and in dotted lines in its vertical position, which latter it must attain in order to move or straighten a partly rolled ingot or billet, while the inclined position is especially adapted to tilt or turn the metal resting on the roller bed.

To change the position of the cheek plate 12, from its inclined to its vertical position, a toggle joint, comprising the lever arm 18, fastened to the shaft 19, and the link 20, is located above each rail 17. The shaft 19 is journaled in bearings formed on the bed plate 16, and is driven a part of a revolution by the beveled pinion 21, meshing with the bevel gear 22, on the square shaft 23, and 11

this part revolution of the shaft 19, is sufficient to either bring the cheek plate into the inclined position as shown in full lines in Fig. 3, or into the vertical position as shown in the dotted lines of the same view. Any intermediate position of the cheek plate 12, however, may be obtained and held indefinitely.

The square shaft 23, is mounted in a bushing 24, which is journaled in the standard 25, fastened to the roller bed or other foundation. This shaft 23 slides in the bushing 24, as the bed plate 16 moves across the width of the roller bed and receives an oscillating motion from the arms 26, keyed to each end of the bushing 24. The arms 26, are connected by rods 27, to a crosshead 28, attached to the plunger 29. The ends of the plunger 29 extend into the opposed hydraulic cylinders 30 and 31, so that when fluid pressure is admitted to the cylinder 30, the plunger 29 through the cross head 28 and rods 27 rocks the arms 26 (in the direction of the arrow in Fig. 5) to turn the square shaft 23. This movement of the shaft 23 causes the bevel gears 22 and 21 to turn the rock shaft 19 and through the toggles, to swing the pivoted cheek plate 12 from its inclined to its vertical position (indicated by dotted lines in Fig. 3). By admitting fluid pressure to the cylinder 31, the plunger 29 is moved from left to right (see Fig. 5) to move the cheek plate 12 from its vertical into its inclined position. The cylinders 30 and 31 are connected by suitable piping through a four way valve to a source of fluid pressure supply.

On top of the hydraulic cylinders 30 and 31, are mounted the spring-controlled bumpers 32, the rods of which contact with a projection 33, on the cross head 28, in its forward and backward movement, and serve to cushion the hard blows due to the operation of the hydraulic plunger in the cylinders 30 and 31.

To move the bed plate with the cheek plate toward and beyond the center line of the roller bed and to push an ingot of short length located at any point within reach of the cheek plate requires mechanism which will insure the movement of the cheek plate to be at all times and points parallel with the center line of the roller bed, and these movements from the initial position at the side of the roller bed toward and beyond the center line thereof are attained by the following means.

Hydraulic cylinders 34 are fixed on suitable bases which are anchored to foundations, and the plungers 35, are secured at their outer ends to the bed plate 16. The cylinders 34 are connected to the same pressure pipe which is controlled by one valve (not shown) so that the two plungers move in unison and move the bed plate 16 laterally toward the center of the roller bed. To

maintain at all times a parallel movement of the bed plate, an equalizing shaft 36, is journaled in bearings, and rocking arms 37 are fixed to said shaft 36. Pivotedly connected at one end to the outer swinging ends of the rocking arms 37 are connecting rods 38 which are pivotally secured at the outer end thereof to the bed-plate 16 to insure a parallel movement of the bed plate. To bring the plate 16 quickly to its initial position at the side of the roller bed, hydraulic pull back cylinders 39 are employed having plungers 40, and secured on the outer end of each plunger 40 is a rack 41 which is guided in a bracket 42 and meshes with one of the gear wheels 43 keyed or otherwise fastened on the shaft 36. The radius of these wheels 43, being very much smaller than the length of the rocking arms 37, the necessary stroke of the rams in the cylinders 39, is very much shorter. To cushion the hard blows on the return movement of the cheek plate, spring controlled bumpers 44, are preferably mounted on the cylinders 34, and the bed plate 16, contacts with the same in bringing the bed plate to rest on its quick return or backward movement. In the movement of the plate laterally across the roller bed, the square shaft 23 slides within the bushing 24, while imparting motion to the tilting mechanism, and both of these movements may be obtained at the same time by opening the valves on the piping leading to the hydraulic cylinders 30 and 34.

The cheek plate 13 is of the same length as the tilting cheek plate 12, but its face maintains at all times a vertical position and at its lower edge is provided with a ledge 45. This ledge or projection 45 facilitates the turning movement of the ingots, slabs, or other shapes when being rolled by preventing any tendency of the shape to rise or carry upward and to jump from the rollers 11 under the action of the cheek plates 12 and 13 on the shape during the turning movements thereof.

Lugs having V-shaped grooves are formed integral with the lower edge of the cheek plate 13, and support the same on the V-shaped rails 17, before described. The devices for accomplishing this moving back and forth across the bed are the same as for the cheek plate 12, and comprise the hydraulic cylinders 46, equalizing shaft 47, 120 rocking arms 48, fastened to the shaft 47, connecting rods 49, connecting the free ends of the rocking arms 48, with the rear of the cheek plate 13, the spring controlled bumpers 50, the pull back cylinders 51, operating 125 the gear racks and gear wheels fastened on the shaft 47 and meshing with the racks.

The operation of my manipulator may be described as follows: After an ingot is brought onto the roller bed, it is shifted lat-

100

95

110

115

130

erally across the rollers 11, by either of the cheek plates 12 or 13, depending upon the position the ingot occupies on the roller bed with regard to any one of the passes in the rolls and through which the ingot is to pass. If the ingot occupies a slanting position in regard to the axis of the roller bed, either one or both of the cheeks may be actuated to bring the ingot in alinement with the bed 10 and the particular pass in the rolls the ingot should enter. If the cheek plate 12 is used only for these side shiftings, it occupies a vertical position as shown in the dotted lines in Fig. 3, but if it is necessary to turn the ingot or bloom, it occupies the inclined position and engages the lower adjacent edge of the ingot, and by continuing the side movement of the cheek 12, the ingot will be tilted, and to complete the turning 20 of the ingot the cheek plate 12 will be brought from the inclined position into any position intermediate its initial inclined and the vertical position. In this way rectangular slabs, which with the former devices 25 were very difficult to turn, can very easily be manipulated, *i. e.*, turned, etc., by using both cheeks 12 and 13, the latter with its ledge 45 forming a stop so that the former can engage the slab and turn the same, if 30 the slab is curved due to the rolling process, etc. Both of the cheeks 12 and 13, having the slab between them, are advanced toward each other and press the same in order to straighten the said slab.

35 It will be understood by those skilled in the art to which my invention relates that modifications may be made within the scope of the appended claims without departing from the spirit of the invention. A cheek 40 plate like the cheek plate 12 may be used in place of the cheek plate 13 when desired and other changes may be made.

Copies of this patent may be obtained for five cents each, by addressing the "Commissioner of Patents, Washington, D. C."

I claim:

1. In a rolling mill, the combination with a roller feed table on which metal being 45 rolled is delivered to the reducing rolls, of a manipulator for moving and turning the metal laterally on said feed table, said manipulator comprising a tilting cheek-plate extending lengthwise parallel with the 50 length of the feed table, means for moving the cheek-plate laterally across the width of the feed table, in positioning metal on the feed table, and independent means for tilting the cheek plate in turning metal supported on the feed table, said independent means comprising a fluid pressure cylinder, 55 a rock shaft operatively connected to said cylinder, and a toggle connecting the rock shaft and tilting cheek-plate. 60

2. In a rolling mill, the combination with a roller feed table on which metal being rolled is delivered to the reducing rolls, of a manipulator for moving and turning the metal laterally on said feed table, said 65 manipulator comprising a tilting cheek-plate extending lengthwise parallel with the length of the feed table, means for moving the cheek-plate laterally across the width of the feed table, in positioning metal on the feed table, and independent means for tilting the cheek-plate in turning metal supported on the feed table, said independent 70 means comprising a fluid pressure cylinder, a rock shaft operatively connected to said cylinder, a toggle connecting the rock shaft and tilting cheek-plate and independent 75 means for moving the cheek-plate in a backward direction.

JOHNSON HUGHES.
